(57) **CLAIM**

The ornamental design for a display panel or portion thereof with a graphical user interface, as shown and described.

DESCRIPTION

This application is related to U.S. patent application Ser. Nos. 62/688,108 and 16/448,452 filed on Jun. 21, 2018 and on Jun. 21, 2019, respectively, entitled “Methods and Apparatuses for Providing Input for Head-Worn Image Display Devices”. The content of the aforementioned patent application are hereby expressly and fully incorporated by reference in their entirety, as though set forth in full.

FIG. 1 is a front view of a display panel or portion thereof with a graphical user interface showing a first embodiment of our design;

FIG. 2 is a front view of a display panel or portion thereof with a graphical user interface showing a second embodiment thereof;

FIG. 3 is a front view of a display panel or portion thereof with a graphical user interface showing a third embodiment thereof; and,

FIG. 4 is a front view of a display panel or portion thereof with a graphical user interface showing a fourth embodiment thereof.

The broken lines depicting a display panel or portion thereof are included for the purpose of illustrating environmental structure and form no part of the design. The broken lines depicting portions of a graphical user interface are included for illustrating environmental aspects of a display panel or portion thereof with a graphical user interface and form no part of the design.
